UNITED STATES PATENT OFFICE.

PHILIP F. RHOADES, OF NEW YORK, N. Y., AND WILLIAM M. WELLING, OF LONG VALLEY, NEW JERSEY, ASSIGNEES TO STANDARD ARMATURE WINDING MACHINE COMPANY, INC., A CORPORATION OF NEW YORK.

ARMATURE-WINDING MACHINE.

1,408,639.

Specification of Letters Patent. Patented Mar. 7, 1922.

Application filed October 22, 1920. Serial No. 418,854.

To all whom it may concern:

Be it known that we, PHILIP F. RHOADES, a citizen of the United States, and a resident of the city of New York, borough of Manhattan, in the county and State of New York, and WILLIAM M. WELLING, a citizen of the United States, and a resident of Long Valley, in the county of Morris and State of New Jersey, have invented a new and Improved Armature-Winding Machine, of which the following is a full, clear, and exact description.

This invention relates to armature winding machines, and has for an object the provision of a machine in which an armature, with the commutator attached, can be rewound in a simple and efficient manner with a maximum saving of time and labor.

Another object of the invention resides in the provision of means whereby with a simple adjustment a plurality of different types of armature windings can be made.

A further object resides in the provision of means whereby an accurate count of the number of armature turns wound at any particular instant may be made.

A still further object of the invention is to provide mechanism whereby during the winding of the armature coils the ends of the coils which are to be connected to the commutator are conveniently led out and held in proper position so that their attachment to the commutator after winding can be achieved in a very simple and efficient manner.

Another object of the invention resides in the particular construction and arrangement of parts to be hereinafter described and claimed in connection with the accompanying drawings.

Our invention in general comprises a rotatable element upon which the armature to be wound and its shaft with commutator attached may be mounted. Associated with this rotatable element is a support for the armature wire which, during the movement of the armature on the rotatable element, guides the wires into the proper slots. Means are provided in certain circumstances to periodically remove the wire support from the path of the armature shaft. Means are also provided and associated with the rotatable element, and to which the ends of a previously wound coil are connected, so

that during the winding of a subsequent coil these ends are firmly held during the winding so that they may be connected to the commutator after all the coils have been wound in a simple and efficient manner.

Further features of the invention will be apparent from a consideration of the following description and claims when taken in connection with the following drawings.

The invention is illustrated in the drawings, of which—

Figure 1 is a side elevation of the machine;

Figure 2 is a plan view of part of the machine, particularly with reference to the means for supporting the armature wire;

Figure 3 is a detail sectional view of the mechanism for actuating the armature wire support;

Figure 4 is a detail view of the indicating means;

Figure 5 is another section taken on the line 5—5 of Figure 4;

Figure 6 is a partial detail view;

Figure 7 is a partial plan view of the means for supporting one end of the armature shaft;

Figure 8 is a section through one end of the support for the armature shaft; and

Figure 9 is a view of the support for another end of the shaft.

As shown in the drawings, the invention comprises a base portion or pedestal 1 having a vertically extended standard portion 2 and a horizontal standard portion 3. The upper rear portion of the standard 3 is provided with a bearing 4 for a shaft 5 which at its outer end is suitably journaled in the main base portion 1. At the upper end of the standard portion 2 there is a horizontally extending platform 6. The front end of the shaft 5, which is hollow, is provided with an enlarged head portion 7 provided with apertures 8 and 9 therein (see Figure 6) through which the ends 10 and 11 of arms 12 and 13 extend. These arms 12 and 13 are spaced apart any required distance by reason of the adjustment of the end portions 10 and 11 of the slots 8 and 9. Any adjusted position of the end portions 10 and 11 may

be fixed by means of set screws 14 and 15 engaging therewith in the head portion 7. Within the shaft 5 is a hollow tube 16 which fits loosely therein and at its rear end is con-

nected by a pin 17 with a plate 18 suitably fastened to the bearing portion 4. Within the tube 16 a needle 19 is adapted to move. This needle is connected at its rear end by 5 a spring 20 with the pin 17. The movement of the needle 19 within the tube 16 is limited by the engagement of a slot 21 in the needle with a pin 22 fastened in the walls of the tube 16. The front end of the needle 19 is 10 provided with a hook portion 23 which, in a manner hereinafter to be described, is adapted for a certain purpose to engage the ends of the armature wires.

Between the pedestal 1 and the bearing 4 15 a power-driven pulley 24 is fixed on the shaft 5. This pulley may be driven by any suitable means, such as a power cable 25. Also fixed on the shaft 5 is a bevel gear 26 adapted to mesh with a bevel gear 27 20 mounted on the lower end of a shaft 28. This shaft is journaled at its lower end in the base portion 1 and at its upper end is journaled in the end of the platform 6. At the extreme upper end of shaft 28 a cam 25 element 29 is carried, the functioning of which will be hereinafter explained. Midway of the shaft 28 is a worm gear 30 30 adapted to mesh with a pinion 31. The worm gear 30 may be formed on a sleeve 30' which can be slipped over the shaft 28 and fastened thereto by any suitable means. The pinion 31 is mounted on a stub shaft 32. This shaft 32 is adapted to be journaled in a block 33 adapted to slide in a slot 34 35 of a bracket 35 extending from the standard 2. The other end of the stub shaft 32 is connected to an indicator or pointer 36 which is adapted to move over the face of an indicator plate 37. This indicator plate is 40 loosely mounted on the stub shaft 32 and, as shown in Figure 4, is connected to the standard 2 by means of a set screw 38 engaging the standard through a slot 39 in the plate 37. The block 33 is provided with 45 flange portions 40 and 41 engaging the lateral faces of the slot 34, whereby the movement of the block 33 and the slot 34 is directed. A pin 42 fastened to a portion of the bracket 35 is adapted to be connected 50 to one end of a spring 43, the other end of which is suitably connected to the stub shaft 32. This spring 43 tends to hold the indicator or pointer 36 in a normal position. A link connection 44 is made with the stub 55 shaft 32 at the end thereof adjacent the indicator plate 37, so that when a pull is exerted on this connection 44 the stub shaft 32 with the pinion 31 thereon is moved backward to draw the pinion 31 out of mesh 60 with the gear 30. At this instant the spring 43 will throw the indicator point back to normal position. This mechanism provides a ready means whereby the counter can be returned to zero position.

65 Between the arms 12 and 13 there is

adapted to be supported an armature 45 in which are the usual slots 46 for the reception of the armature coils. This armature is mounted on a shaft 47 and the ends of the shaft are suitably supported in the ends 70 of the arms 12 and 13. One end of the shaft 47 is supported on the arm 13 and is gripped between blocks 48 and 49 suitably seated in an aperture in the end of the arm 13 and adjustable by means of set screws 75 50 to clamp the blocks against the shaft 47. The other end of the shaft 47 is supported on the end of arm 12 and is gripped between blocks 51 and 52 which are slidable in a rectangular frame 53 and are adjusted 80 against the shaft 47 by means of set screws 54. This rectangular frame 53 is connected by pins 55 to a ratchet wheel 56 and moves therewith. This ratchet wheel is held in any particular position by a pawl 57 backed 85 by a spring 58, both the pawl and the spring being pivoted on the end of arm 12. The ratchet wheel 56 is connected to a bushing or sleeve 59 which extends through a suitable aperture in the end of arm 12 and is 90 threaded on its other end. This threaded portion is adapted to be engaged by an inferiorly threaded collar 60 whereby the bushing 59 and the ratchet wheel 56 may be rigidly clamped to the end of arm 12. By 95 reason of the fact that the rectangular arm 53 rigidly grips the end of shaft 47, and this rectangular frame is rigidly connected to the ratchet wheel 56, the shaft 47 is moved whenever the ratchet wheel 56 is moved. 100 This is for a purpose hereinafter to be described.

In Figure 1 the slots 46 are shown extended in a direction parallel to the axis of the shaft 47, although in different types of 105 armatures these slots may extend in different directions. For instance, they may extend in a direction from right to left, as viewed in Figure 1, making an angle with the direction of their position shown in Figure 1. 110 It is desired to wind the wire 61 into the slots 46 in the desired manner, and in order to do this as rapidly as possible there is provided a holder or support for the wire 61 which is in the form of a bell-crank lever 115 having an arm 62 depending from the pivot point 63 on the platform 6. On the lower end of this arm 62 is an adjustable plate 64 having pulleys 65 and 66 suitably positioned thereon and over which the wire 61 is adapted to run. The other end of the bell-crank lever is provided with an arm 68 extending rearwardly above the platform 6 and having on its end an adjustable plate 68. This adjustable plate is suitably apertured to receive a bushing or sleeve 69 within which a shaft 70 extends. This shaft is provided on its lower end with a cam roller 71 and on its upper end is threaded. Over this threaded portion a cap 72 extends and is suitably 130

apertured to receive a threaded stem 73 of a thumb nut 74. The lower end of this threaded stem 73 has an enlarged head portion thereon suitably seated in a co-operating groove 75 in the upper end of the shaft 70. By manipulating the thumb nut 74, the position of the shaft 70 within the bushing sleeve 69 can be adjusted. This adjustment varies the stroke of the bell-crank lever and thereby varies the movement of the adjustable plate 64 carrying the wire.

In winding the form or armature shown in Figure 1, the arms 12 and 13 are rotated, and it is desired to wind a coil in the slot 15 shown in line with the shaft and in one directly opposite on the opposite side of the shaft. To do this the end of the adjustable plate 64 must lie in line with the shaft during the time that the wire 61 is being led in each slot. However, when the shaft is rotated there is a point of time in its rotation when it would contact with the end of the plate 64. To avoid this, the plate 20 is moved out of the line of travel of the shaft 47 for an instant each time that its engagement is about to take place. This lateral movement of the wire support is effected by the movement of the bell-crank lever through the action of a cam roller 25 71 in relation to a cam element 29 disposed on the upper end of shaft 28. This cam element is provided with a plurality of cams 76 and 77 thereon. The roller 71 is shown contacting with the cam 76, the curvature of which 30 is so distinct as to cause a lateral movement of the wire support of plate 64 at the instant in the rotation of the shaft 47 when the shaft would otherwise contact with the wire support. Immediately after the shaft 35 has passed this point in its travel the wire support is moved back into its proper position in line with the slot in which the slot 40 is being led. A spring 78 is disposed between the arm 67 and the platform 6 to effect the movement of the arm 67 in one direction. If the slots are inclined at an angle to the axis of the shaft, of course the movement of the wire support may be effected by varying the shape of the cam in any well-known 45 manner. It will be observed, in Figure 1 particularly, that the cam 77 is of a different shape than the cam 76 and is designed to give a movement of the wire support which will be suitable for winding armature coils 50 in the sloping slots above mentioned. The wire is produced from a reel 79 which is mounted on a suitable standard 80 on the platform 6. It then extends over a pulley 81 mounted on an arm 82 extending from 55 the end of the platform 6. The wire then extends over the pulleys 66 and 65 previously mentioned.

In the operation of the device the wire is threaded through the support, as shown, and 60 one end of it is fastened to the shaft 47 and

then placed in one of the slots 46 which has been positioned, as shown, corresponding to the position of the slot designated 46' in Figure 1. It is desired to wind the armature coil in this slot 46' and in the slot opposite 70 it on the other side of the shaft. After having fastened the end of the wire to the shaft by any suitable means, the shaft 5 is rotated in the proper direction to rotate the arms 12 and 13 and with them the armature. As the shaft 47 moves from the position shown in Figure 1, the cam action above described momentarily moves the end of the wire support out of the path of the shaft and then moves it back immediately into 80 its proper position again ready to lead the wire in the slot on the opposite side of the armature. After the required number of turns have been wound in any particular slot, the wire is pulled and a loop thereof 85 is led over to the hook 23 of the needle 19, as shown in Figure 1. The remaining portion of the wire is then introduced into a new slot. This new slot is moved into the position occupied by the slot just wound by 90 moving the ratchet wheel 56 the desired distance to bring the slot into position. In order to move the ratchet wheel, the upper support for the shaft 47, shown in Figure 9, must be released slightly to permit the 95 movement of the shaft, but the lower gripping members 51 and 52 need not be released since they move with the ratchet wheel 56. It will, therefore, be observed that while the next slot is being wound with its coils 100 that the ends of the wires, which have as above described been pulled out and connected to the hook 23, are being twisted. This twisted condition is shown in Figure 1 and represents the condition of the wires 105 such as adapt them very readily to be soldered to the particular commutator section to which they are to be connected. As each slot is wound with a coil the ends are drawn out and connected in turn to the hook portion 23, so that when the complete winding on the armature is finished there will be a plurality of twisted ends projecting from one end thereof which are to be properly insulated and later soldered to the commutator section. 110

It will also be observed that by supporting the armature on its frame, comprising the arms 12 and 13, and winding with this mechanism it is not necessary to remove 115 the commutator therefrom. This particular provision of the apparatus shown makes it a very simple matter to rewind an armature or motors and generators in repair shops; and this can be done at high speed 120 since by reason of the cam portion of the wire support this support moves out of the way of the armature shaft during its revolution at whatever speed it attains.

While only one form of armature wind- 125

ing is shown, it will be apparent that many different forms of windings may be placed on the armature by this machine, and these various forms and manners of winding can 5 be wound by this machine without materially varying the apparatus or the principle of its operation which constitute our invention.

What we claim is:

- 10 1. An armature winding machine comprising means for supporting an armature, means for winding a succession of coils having loops therebetween on the armature, means for holding one of the loops between 15 a previously wound coil and the next coil while the next coil is being wound, and means for causing the twisting of said loop during the winding of the next coil.
- 20 2. An armature winding machine comprising a support on which the armature is to be rotated, a hollow shaft connected to said support, means for winding on the armature, during the rotation of the support, armature coils with a loop between 25 each coil, a needle within the hollow shaft, a hook on said needle to hold the loops between the coils, a spring tending to pull the needle within the shaft, and means to rotate the armature and effect the twisting of the 30 loop held by the needle.
- 35 3. An armature winding machine which comprises a pair of arms spaced apart but parallel and adapted to support an armature thereon, the end of each arm provided 40 with an aperture to receive the armature shaft, shaft gripping means disposed in each aperture and means on the end of one of said arms to adjust the position on the shaft gripping means on said arm whereby the angular position of the armature can be changed without removing it from the arms.
4. An armature winding machine which

comprises a horizontally disposed rotating shaft, a support for said shaft, a hub having apertures disposed on the end of said shaft, a pair of arms having main portions off-set from but extending parallel to the shaft and right angle end portions extending through the apertures in the hub and means for adjustably fastening the end portions of the arms in the hubs with respect to the shaft. 45

5. An armature winding machine which comprises a horizontally disposed rotating shaft, a support for said shaft, a hub having apertures disposed on the end of said shaft, a pair of arms having main portions off-set from but extending parallel to the shaft and right angle end portions extending 60 through the apertures in the hub and means for adjustably fastening the end portions of the arms in the hub with respect to the shaft, and means on the end of each arm to grip and support the armature shaft. 65

6. An armature winding machine comprising means for supporting an armature, means for winding a succession of coils having loops therebetween on the armature, and stationary means for holding the loops between the coils while the armature is being wound, whereby said loops are twisted. 70

7. An armature winding machine comprising a stationary frame, means on said frame for supporting and rotating an armature, means for winding a succession of coils having loops therebetween on the armature, stationary means attached to the frame for holding the loops between a previously wound coil and the next coil 80 while said next coil is being wound, and means for causing the twisting of said loop during the winding of the next coil. 75
